UNITED STATES PATENT OFFICE

WILLARD N. SAWYER, OF WINCHESTER, MASSACHUSETTS, ASSIGNOR TO UNITED SHOE MACHINERY CORPORATION, OF PATERSON, NEW JERSEY, A CORPORATION OF NEW JERSEY

HEEL-MAKING MACHINE

Application filed May 5, 1928. Serial No. 275,508.

This invention relates to heel making machines and is illustrated as embodied in a wood heel turning machine of the type disclosed in United States Letters Patent No. 1,488,534, granted April 1, 1924, on the application of Folsom, Vinton and Whitney.

Machines of this type are provided with two rotary cutters and a jack for holding a heel blank, the blank being swung past one cutter by the jack to make a cut around one side of the heel blank from breast to back and then past the other cutter to cut around the other side of the blank. It has been customary to clamp the heel blank in the jack by its toplift and heel seat surfaces and to gage it only by a gage at its breast surface, since the lateral and rear surfaces of the blank were about to be trimmed by the cutter. Such a gage affords no certainty of lateral positioning of the blank, this being entirely a matter of the operator's judgment. Under some conditions this circumstance has resulted in inferior work inasmuch as the lateral surface thus formed on the blank sometimes lacked proper relationship to other surfaces formed thereon. This was especially true in the case of Cuban heels, in which the previously formed breast groove is vertical, and a slight lateral displacement of the blank in the heel turning machine would put the side and breast surfaces hopelessly out of proper relationship.

This problem has been satisfactorily dealt with by the invention of A. F. Cook disclosed in his application Serial No. 274,583, filed May 2, 1928. Cook provided, in addition to the usual breast gage, a side gage arranged to contact with a lateral face of a wood heel blank and removable from operative position after the blank had been gaged to permit the trimming cutter to form the lateral heel surface on the blank, the gage being moved from operative to inoperative position by a handle. It is an object of this invention to improve still further the construction provided by the invention of Cook. To this end I have provided an organization comprising, as illustrated, a single handle for clamping the heel blank in the jack, for moving a side gage from operative to inoperative position, and

preferably also for operating the jack, thus simplifying to a considerable degree the construction and operation of the machine.

In accordance with another feature of the invention, the illustrated gage is pivoted on an axis oblique to the gaged face of the heel blank so that as it is swung from operative position it will separate from the gaged surface by the initial portion of its movement, thus avoiding any possibility of disturbing the gaged blank by dragging along its surface.

These and other features of the invention comprising certain combinations and arrangements of parts will be apparent from the following description of a preferred embodiment of the invention shown in the drawings, in which

Figs. 1 and 2 are side views of so much of a machine of the type referred to as is necessary to an understanding of the present invention and showing the side gage in retracted and in operative position, respectively; and

Figs. 3 and 4 are similar views taken from the front of the machine.

The jack 10 of the illustrated wood heel turning machine is supported on a jack holding shaft 12 pivoted to the machine by means of a bracket or crane not shown herein but fully set forth in the Letters Patent referred to. The jack is pivoted to a plate 14 at the top of the shaft 12 by a horizontal pin 16 to permit vertical tilting of the jack. The jack carries a base plate 18, on which a wood heel blank 20 is placed against a breast gage 22, adjustable by a slot and bolt connection at 24. An upper clamping member 26 is pivoted to move vertically above the blank 20 and is forced against it by pressure from a screw 28 swiveled in the end of a compound lever 29, 30 pivoted on the jack frame at 32. A roll 34 at the end of the lever 28, 30 is engaged by a cam 36 at the end of a lever 38 pivoted on the jack frame at 40, to rotate the lever 28, 30 and set the clamping member 26, thereby holding the blank against the base plate. This clamping structure will be found more fully described and claimed in United States Letters Patent No. 1,707,985, granted

April 9, 1929, on an application filed by N. W. Kinney.

In operation, the jack is swung toward the cutter 42 and then is rotated about the axis of the shaft 12 by means of the lever 38 to cause the cutter to trim the blank 20 from the breast 44 along one side to the back 46, the other side of the blank being then treated in the same manner. As above explained it is highly desirable that the blank should be gaged from the side as well as from the breast, and to this end I have provided an improved side gage 48 of the type which is removable from the path of the cutters after its gaging function is performed.

This gage 48 is mounted fixedly on a stub shaft 50 rotatable in the jack frame. The stub shaft is not quite horizontal, extending a little downwardly and outwardly from the jack frame. An adjustable contact member 52 is mounted in the gaging end of the member 48. A link 54 is pivoted to the gage and to a boss 56 on the operating lever 38.

When the lever 38 is swung up, as shown in Fig. 2, to loosen the lever 28 and release the blank 20, the boss 56 swings to the right and throws the gage 48 clockwise until its left end 58 comes up under a stop 60. Its gaging end will then be opposite the side of the newly inserted heel blank 20 which can be laterally gaged by the contact member 52. When the lever 38 is thrown down, as shown in Fig. 1, to clamp the heel, it swings the gage 48 up away from the side of the blank 20, so that the cutters 42 can cut the surface lately engaged by the side gage. Owing to the slope of the shaft 50 this upward movement of the gage 48 has an outward component so that the contact member 52 immediately moves laterally away from the blank 20 as it begins to move upward (Fig. 3), thus avoiding any disturbance of the blank as the gage is removed.

A coil spring 62, wound around the shaft 50 and connecting it to the frame of the jack, tends to hold the gage in operative position, and a pin and slot connection 64 between the link 54 and the boss 56 insures that the gage shall reach its operative position irrespective of accurate positioning of the lever 38 when the jack is unclamped.

Having described my invention, what I claim as new and desire to secure by Letters Patent of the United States is:

1. In a heel cutting machine, a jack arranged to clamp a heel blank, and a pivotally mounted gage arranged to contact with a surface of the blank and to be swung to an inoperative position after the blank has been gaged, the pivotal axis of the gage being substantially oblique to the gaged surface of the blank whereby the gage will move out of contact with said surface in its initial movement toward inoperative position.

2. In a wood heel cutting machine, a jack

arranged to hold a heel blank, a lever for causing the jack to clamp the blank, and a gage arranged to engage the blank, said gage being moved from the gaged surface of the blank by the blank clamping lever.

3. In a wood heel cutting machine, a jack arranged to hold a heel blank, a lever for causing the jack to clamp the blank, and a gage arranged to engage a lateral surface of the blank, said gage being moved from the gaged surface of the blank by movement of the lever in clamping the blank.

4. In a wood heel cutting machine, a jack arranged to hold a heel blank, a lever for causing the jack to clamp the blank, a gage arranged to engage the blank, and connections between the gage and the lever whereby movement of the lever in clamping the blank moves the gage from the surface gaged thereby.

5. In a wood heel cutting machine, a cutter, a jack arranged to hold a heel blank, a lever for operating the jack to carry a heel blank therein past the cutter, a pivoted gage arranged to swing into and out of engagement with the heel blank, and a link connecting the gage with the operating lever whereby the lever operates the gage.

6. In a wood heel cutting machine, a jack arranged to clamp a wood heel blank, a pivoted gage arranged to swing past a side face of a blank in the jack, and a stop on the jack arranged to arrest the swinging movement of the gage when it reaches operative position.

7. In a wood heel cutting machine, a jack arranged to clamp a wood heel blank, a pivoted gage arranged to swing into and out of engagement with a side face of a blank in the jack, a stop on the jack arranged to arrest the swinging movement of the gage when it reaches operative position, and a spring for holding the gage in operative position.

8. In a wood heel cutting machine, a cutter, a jack for clamping a heel blank and moving it past the cutter, a gage for gaging a surface of the blank, and movable from gaging position, and a single means for causing the jack to clamp the blank and for moving the gage from gaging position prior to the trimming of the gaged surface by the cutter.

9. In a wood heel cutting machine, a cutter, a jack for clamping a heel blank and moving it past the cutter, a gage for gaging a surface of the blank, and movable from gaging position, and a single means for causing the jack to clamp the blank and for moving the gage from gaging position prior to the presentation of the heel blank to the cutter.

10. In a heel cutting machine, a jack arranged to clamp a heel blank, a movable gage arranged to gage a surface of the heel blank, and means for moving the gage along the

gaged surface, constructed and arranged to separate the gage from the gaged surface during the initial portion of its movement.

11. In a wood heel jack, a heel blank support, actuating means to open and close said jack relative to said support, a side gauge for a heel blank on said support, and connections from said actuating means to said gauge, effective to move said gauge to operative and inoperative positions as said jack is opened and closed.

12. In a wood heel jack, a heel blank support, actuating means to open and close said jack relative to said support, a side gauge for a heel blank on said support, and means to advance said gauge to operative position as the jack is opened and to withdraw said gauge after a clamping pressure has been applied to the newly inserted heel blank.

13. In a wood heel jack, a heel blank support, actuating means to open and close said jack relative to said support, a side gauge for a heel blank on said support, and a connection from said actuating means to said gauge effective to move said gauge forward and rearward as said actuating means is moved to open and close said jack, said connection including a lost motion element, whereby said gauge will be moved in each direction as the actuating means approaches its limit of travel in the corresponding direction.

14. In a wood heel jack, a heel blank support, a hand lever to open and close said jack relative to said support, a side gauge for a heel blank on said support, and a connection from said hand lever to said gauge effective to move said gauge forward and rearward as said hand lever is moved to open and close said jack.

40 In testimony whereof I have signed my name to this specification.

WILLARD N. SAWYER.
